UNITED STATES PATENT OFFICE.

ABRAHAM PODEL, OF LONG ISLAND CITY, NEW YORK, ASSIGNOR TO ANCHOR CAP AND CLOSURE CORPORATION, OF LONG ISLAND CITY, NEW YORK, A CORPORATION OF NEW YORK.

CAP OPENER.

Application filed November 17, 1925. Serial No. 69,565.

The present invention relates broadly to uncapping tools and more especially to a cap opener stamped from sheet metal and adapted particularly for opening caps provided with rubber gaskets, etc.

Cap openers have heretofore been constructed of sheet metal in the form of either flat members or flat sided members with marginal webs stamped around the edge of the opener. The end of a flat opener which rests on the top of the cap has a tendency to puncture the top of the cap particularly where the cap is of large size and relatively thin metal, as is the common practice of today in connection with vacuum sealed caps.

Where the cap is punctured, it is practically useless for temporarily resealing while the contents of the package is being used up.

Cap openers provided with flanges around the edge require expensive dies for manufacture and the wear on these dies is excessive, so that the manufacture of such openers becomes expensive. Furthermore, such openers take more metal than a flat 25 opener and do not lie flat when shipped, all of which adds to the ultimate cost.

The present opener combines the advantages of the prior known sheet metal types and at the same time obviates the disadvantages thereof. The opener comprising the present invention is in the main stamped from flat sheet metal and the fulcrum portion of the opener is widened in the form of a slight flange to provide a relatively wide 35 surface to rest upon the cap top as one of the points of leverage. In the preferred form of the opener, the lip which engages the underneath of the cap is provided with a lateral projection adapted to bite into a 40 rubber gasket or the like, such as is commonly used in hermetic seal caps, and under the edge of the cap so that there is no tendency of the opener to slip off the cap when the opener is in use.

Fig. 1 illustrates the preferred form of the opener in a perspective view and in dotted lines shows how such openers may be nested for shipment.

Fig. 2 illustrates the preferred form in 50 a fragmentary view showing its cooperation with one common type of vacuum sealed caps.

Fig. 3 is a detailed view of the head of the opener.

Fig. 4 is a perspective view of another 55 form of the opener showing a curved handle and omitting the gasket engaging lip.

Fig. 5 illustrates the operation of the opener when in use.

Referring now to the drawings and more 60 particularly in Figs. 1, 2, and 3, the opener comprises a body portion 1 of flat sheet metal terminating in a fulcrum extension 2 which is provided with a curved fulcrum shoe adapted to rest upon the top of a cap 65 A, (illustrated in Figs. 2 and 5 in dotted lines). A cap engaging hook 5 is disposed beneath and laterally off-set from the shoe 4 with a recess 6 provided between the cap engaging hook 5 and the fulcrum exten- 70 sion 2.

In the preferred form, a gasket engaging lip 7 extends laterally from the cap engaging hook 5 in such manner as to tend to bite into a gasket B, (illustrated in dotted lines 75 in Fig. 2), so that there is no tendency of the hook to pull out from under the cap, and furthermore, the construction provides a wide face for the cap skirt engaging hook so that there is less tendency for this member to disrupt and cut the side or skirt of the 80 cap A.

The opener illustrated in Figs. 4 and 5 is similar to that shown in Figs. 1, 2, and 3 with the exception that the gasket engaging 85 lip is omitted. In Fig. 5, an end view of the opener is illustrated as being grasped in the right hand of a user. The normal tendency of the user in applying an opener of this kind is to twist the opener slightly 90 clock-wise as indicated by the arrow X in Fig. 2. This twisting motion brings into operation the shoe 4 which prevents the fulcrum portion of the opener from puncturing the top of the cap A, at the same time, this rolling action of the hand causes the lip 7 to firmly engage beneath the skirt of the cap so that the device is very effective to 95 remove caps of this character.

It will be observed that since the major portion of the opener is flat, that such openers may be stacked one upon the other with their flanges 4 and extending lips 7, adjacent one another as indicated by dotted

lines in Fig. 1, thereby facilitating the packaging of the openers for shipping purposes.

Having thus described my invention, 5 what I claim is:

1. A cap opener comprising a substantially flat body portion provided with an integral forwardly extending fulcrum portion, a curved fulcrum shoe on the lower 10 part of the fulcrum portion, a cap engaging hook disposed beneath said fulcrum portion, and a projecting lip on the end of said hook, said shoe and said lip both extending laterally on the same side of said body portion.

2. A cap opener formed from a single piece of sheet material and comprising a substantially flat body portion provided with an integral forwardly extending fulcrum portion, a curved fulcrum shoe on the lower 20 part of the fulcrum portion and extending laterally therefrom, a substantially flat cap engaging hook member disposed beneath said fulcrum portion, and a laterally pro-

jecting lip formed by bending the end of 25 said hook.

3. A cap opener comprising a substantially flat member having a longitudinally extending body portion with a fulcrum portion integral with the body portion, said fulcrum portion being provided with a curved laterally extending shoe, a substantially flat cap engaging hook member disposed beneath said fulcrum portion and having its end bent to extend at substantially 30 right angles from the plane of the body portion.

4. An article of manufacture, a cap opener having a substantially flat body portion adapted to be edgewise disposed when 40 applied to a cap, a fulcrum member at one end of said body portion, adapted to rest on a substantially flat cap, and a cap engaging hook member, beneath said fulcrum, the end of said hook being bent to form a laterally 45 extending lip for engaging a cap.
